JEWELLED BROOCH

Helen M. Lund, 15 Brentwood Ave., and Gilda S. Vitulli,
113 Sharon St., both of Providence, R.I.

Filed Dec. 16, 1959, Ser. No. 58,683

Term of patent 14 years

(Cl. D45—19)

Figure 3 is a sectional view taken on the line 3—3 of Figure 1, showing the structure and relative proportions of the design in depth, with the parts not cut by the section being illustrated in dotted lines.

We claim:

The ornamental design for a jewelled brooch, as shown and described.
